UNITED STATES PATENT OFFICE.

FRANZ FRIEDRICH KRUCKENBERG, OF HEIDELBERG, GERMANY, ASSIGNEE TO LUFT-FAHRZEUGBAU SCHÜTTE-LANZ, OF MANNHEIM-RHEINAU, GERMANY.

BALLAST BAG FOR AIR VESSELS.

Application filed August 18, 1922. Serial No. 582,135.

To all whom it may concern:

Be it known that I, FRANZ FRIEDRICH KRUCKENBERG, of Heidelberg, Germany, have invented a new and Improved Ballast Bag for Air Vessels; and I do hereby declare the following to be a full, clear, and exact description of the invention, such as will enable others skilled in the art to which it pertains to make and use the same.

10 In airships water is used as ballast which is usually kept on board in tanks or in bags of waterproof fabric. These bags may be emptied, when desired, by means of valves or other devices and the ballast discharged 15 in such quantities as the circumstances require. The discharging of the ballast takes some time, depending upon the free space given by the valve or releasing device. Situations, however, occur when it is necessary 20 to discharge a large quantity of ballast immediately. For these purposes special bags have been used or employed having devices more or less complicated in order to try and meet such conditions.

25 My invention relates to an improvement in ballast bags and has for its object to provide a ballast bag which is simple, inexpensive and durable in construction and easy to manipulate.

30 The invention consists in the several features and in the construction, and arrangement of such features as more fully herein-after described and claimed.

Referring to the drawings:—

35 Fig. 1 is a side view.

Fig. 2 is a central vertical cross section.

Fig. 3 is a central vertical section of a modified form of the invention.

40 Fig. 4 is a central vertical section of another modified form of the invention.

In the drawings, in which like reference characters denote like parts throughout the several views:—

45 Fig. 1 shows the ballast bag as having a body with a lower end 1, means 2 for suspending it from a suspension device at its upper end and a loop 3 at the lower end spanning a discharge opening 3^a.

50 The lower portion of the ballast bag is, preferably, tapered downwardly in order to provide sufficient space for the ballast, when the lower end of the ballast bag is drawn up within the bag and also to facilitate the discharge of ballast.

55 Fig. 2 shows the ballast bag filled with

ballast, and ready for use, the lower end 1 being drawn up into the interior of the bag, and by means of a loop 3 attached to a holding and releasing device 4, which may be in the shape of a hook or other suitable means.

When it is desired to discharge the ballast from the bag the holding and releasing device 4 is disengaged from the loop 3, whereupon the weight of the ballast forces the lower end of the bag downward and outward, into the position shown in Fig. 1, when the ballast will be discharged from the discharge opening 3^a.

Fig. 3 shows a modified form of the invention in which a section of hose or pipe 5 is attached to the bag at a point 7. Fig. 3 also shows means whereby the quantity of ballast discharged from the bag may be regulated.

Fig. 4 shows a pipe 8 attached to the edge of the discharge 3^a of the bag for the purpose of directing the discharge of ballast from the bag and also holding the discharge opening 3^a normally open.

Figs. 3 and 4 also show means whereby the quantity of ballast discharged from the bag may be regulated, which means consists of a pulley 9, and a rope or cable 10 which runs over the pulley 9, one end of 35 the rope or cable being secured to the loop 3 of the bag, while the other end extends to a point within easy reach of the operator.

In operation when the discharge opening 3^a is lowered to the desired height, below 90 the level of the ballast in the bag, the ballast will be discharged until the level of the ballast falls below the level of the discharge opening, when the discharge of ballast will stop.

95 Referring to the operation of the invention shown in Figs. 3 and 4, by paying out the rope or cable 10 the upper end of the pipe 8 is lowered to the desired height, below the level of the ballast, when the ballast will be discharged until the level of the ballast falls below the level of the pipe 8. Thus it will be seen that by adjusting the position of the discharge opening 3^a the quantity of ballast discharged may be 105 regulated.

I do not desire to be understood as limiting myself to the specific details of construction and arrangement as herein described and illustrated, as it is manifest 110

that variations and modifications may be made in the features of construction and arrangement in the adaptation of the device, to various conditions of use, without departing from the spirit and scope of my invention and improvements. I therefore reserve the right to all such variations and modifications as properly fall within the scope of my invention and the terms of the following claims.

What I claim is:—

1. In a ballast receptacle for airships, a bag provided with a bottom discharge opening and means located interiorly of the bag connected to the bottom thereof for vertically elevating and lowering the said bottom, thereby regulating the quantity of ballast discharged through said discharge opening.
2. In a ballast receptacle for airships, a bag provided with a bottom adapted to be upturned within the interior of said bag, said bottom provided with a discharge opening and means located interiorly of the bag connected to the bottom thereof for vertically elevating and lowering the said bottom and thereby regulating the quantity of

ballast discharged through said discharge opening.

3. In a ballast receptacle for airships, a bag provided with a bottom discharge opening, means located interiorly of the bag connected to the bottom thereof for vertically elevating and lowering the said bottom and thereby regulating the quantity of ballast discharged through said discharge opening and means for directing the discharge of ballast therefrom.

4. In a ballast receptacle for airships, a bag provided with a bottom discharge opening, means located interiorly of the bag connected to the bottom thereof for vertically elevating and lowering the said bottom and thereby regulating the quantity of ballast discharged through said discharge opening and means for holding said discharge opening open.

Witness my signature this 6th day of July, 1922.

FRANZ FRIEDRICH KRUCKENBERG.
